Harry Q. Schroeder
ATTORNEY.

UNITED STATES PATENT OFFICE

ANDREW M. WIEHL, OF SAN FRANCISCO, CALIFORNIA, ASSIGNOR OF ONE-HALF TO
HARRY R. BAUMANN, OF OAKLAND, CALIFORNIA

INTERFERENCE ELIMINATOR FOR RADIORECEIVERS

Application filed July 2, 1929. Serial No. 375,492.

The invention is for a radio interference 5
eliminator. It is found exceedingly difficult
to obtain satisfactory reception over a radio
in many localities due to the presence in prox-
imity to the receiving point of high tension
electric wires, such for instance, as trolley
wires, electric power feeder wires and the
like, due to the radiating from such wires
of an electric current.

10 It is one of the objects of the invention to
provide an interference eliminator for radios
that will be particularly effective in eliminat-
ing radio interference resulting from alter-
nating current waves from high tension elec-
tric power lines and the like.

15 The invention will be hereinafter fully set
forth and particularly pointed out in the
claims.

In the accompanying drawings; Figure 1
20 is a perspective view showing the inter-
ference eliminator unit mounted in a suitable
casing.

Figure 2 is a wiring diagram showing the
manner of electrically connecting the various
25 elements comprising the eliminator.

Figure 3 is a wiring diagram indicating
the manner in which the eliminator is em-
ployed with a radio receiving set.

For a clearer and more comprehensive un-
30 derstanding of the device reference may now
be had to the drawing. In its general or-
ganization the invention contemplates a radio
frequency amplifier designated by the refer-
ence character 10 and is associated with a
35 connector 11 connected thereto by cable 17.
The amplifier 10 is of the usual type of con-
struction having a grid 12, plate 13, and fila-
ment 14 which is provided with negative and
positive terminals 15 and 16 respectively. In
40 the interest of economy the connector 11 may
be formed from a used radio tube base hav-
ing a plate contact pin 18, a grid contact pin
19, a negative filament contact pin 20 and a
positive contact pin 21, the circuit wires
45 leading from which are preferably inclosed
in the cable 17 for convenience of introduc-
tion into the casing 39 where the wires are
separated for connection with the various ele-
ments within the casing. Wire 22 connects

50 the plate 13 with contact pin 18. Wire 23

connects the grid 12 with the grid contact
pin 19. Wire 24 connects the negative fila-
ment terminal 15 with the negative filament
contact pin 20. Wire 25 connects the posi-
tive filament terminal 16 with the positive 55
filament contact pin 21. Wire 26 connects
the positive filament wire 25 with antenna
terminal 33 of a radio receiving set.

In order to hook up the device to a radio
set the first radio frequency amplifier is with-
drawn from its socket and the connector 11 is
inserted therein, when the wire 26 may be
connected to the antenna terminal 33 of the
radio receiving set and the wires 30 and 31
connected to the outside aerial 32. Wire 30
connects the grid 12 to the antenna 32. A
variable condenser 29 is connected between
the antenna 32 and the plate 13 by the wire
31. It will be understood that the term
"antenna" is used in its broadest sense. 70

In Figure 3, the grid terminal G, the plate
terminal P and the filament terminal F, of
the socket usually occupied by the electron
tube in the first step of the radio frequency
amplifying portion of a radio receiving set, 75
are indicated as connected to corresponding
terminals of the electron tube 10 when the
connector 11 is in place in the receiving set.
It will be understood that the wiring dia-
gram of the circuit elements of the radio
receiving set is conventional. 80

A rheostat 27 is connected by wire 26 in
series connection between the filament 14 and
the antenna terminal 33 of the radio-receiving
set, and is adjustable to eliminate noise 85
in the receiving set caused by the high tension
power lines. A rheostat 28 is connected by
wire 22 between the plate 13 and the plate
terminal P, and is adjustable to control the
volume of the output of the receiving set, and
to control oscillations in the circuits imme- 90
diately associated with the eliminator.

I claim:

In combination with a radio receiving set
having a radio frequency amplifying stage,
an electron tube having a plate, a grid, and
a filament, a condenser connected in parallel
with the said plate and the said grid, antenna
means connected to the said grid, conductor
means connecting the said plate, grid and fila- 100

ment respectively to the plate, grid and filament terminals of the tube socket of the radio frequency amplifying stage of the receiving set and from which socket an electron tube
5 has been removed, and a rheostat connected between the filament of the first named electron tube and the antenna terminal of the receiving set.

10 In testimony whereof I have affixed my signature.

ANDREW M. WIEHL.
